LOWER ALKYL 4-PHENYL-1-(3-PHENYLPROPYL) PIPERIDINE-4-CARBOXYLATES AND THEIR PREPARATION

Bill Elpern, Walnut Creek, Calif., assignor to Sterling Drug Inc., New York, N.Y., a corporation of Delaware

No Drawing. Application September 12, 1955
Serial No. 533,889

8 Claims. (Cl. 260—294.3)

This invention relates to organic compounds and their preparation, and is concerned with an improvement in the substituent attached to the nitrogen atom of the piperidine ring in the class of chemical compounds identified as lower alkyl 4-phenyl-1-(hydrocarbyl)piperidine-4-carboxylates. In particular, it is concerned with lower alkyl 4-phenyl-1-(3-phenylpropyl)piperidine-4-carboxylates, their acid addition salts, and the preparation of these compounds.

Attempts have been made for some time to develop analgesics having high activity. The highly potent morphine has the disadvantages of causing nausea, vomiting, constipation and respiratory depression, and for these reasons has been supplanted largely by meperidine, ethyl 4-phenyl-1-methylpiperidine-4-carboxylate, especially in obstetrics where depression of respiration is highly undesirable. Because of the relatively high dose required, meperidine has to be injected in hypertonic concentrations, with a consequent risk of irritation at the site of administration. This limits the choice of concentrations which can be used and restricts undesirably the free choice of optimum dosage. This situation is advantageously modified with the compounds of my invention since they are many times more potent as analgesics than meperidine and thus can be administered in smaller volumes of solution and at higher therapeutic levels of effectiveness without making the solution hypertonic. This reduces any tendency to undesirable accompanying irritation, and improves the therapeutic usefulness of the medicament.

U.S. Patent 2,167,351 broadly shows lower alkyl 4-aryl-1-(substituted)piperidine-4-carboxylates where the 1-substituent is a monovalent hydrocarbon radical. Included among the specific examples are such compounds having 1-methyl and 1-benzyl substituents, the latter being of primary value as intermediates for the former. The 1-methyl compounds are now known and accepted as effective, morphine-like central analgesics and atropine-like smooth muscle neurospasmolytics in the relief of severe pain. An outstanding example of these 1-methyl compounds is the commercially available meperidine hydrochloride, ethyl 4-phenyl-1-methylpiperidine-4-carboxylate hydrochloride. On the other hand, the intermediate 1-benzyl compounds have been found to have a decidedly lower analgesic activity compared with the 1-methyl compounds. For example, ethyl 4-phenyl-1-benzylpiperidine-4-carboxylate as its hydrochloride has been found to be only approximately one-fourth as effective an analgesic as meperidine hydrochloride when tested by the Bass-Vander Brook modification of the D'Amour-Smith method. This decrease in activity in going from 1-methyl to 1-benzyl would indicate that 1-phenylalkyl substituents are undesirable, and would thus lead investigators away from these compounds. This actually has been the case in the past twenty years—until I investigated the compounds of this invention.

I have now prepared lower alkyl 4-phenyl-1-(3-phenylpropyl)piperidine-4-carboxylates and surprisingly found

2

them to be outstandingly superior as analgesics compared with the corresponding 1-benzyl compounds of U.S. Patent 2,167,351 and, indeed, many times more effective than the corresponding 1-methyl compounds, even meperidine itself. For example, my ethyl 4-phenyl-1-(3-phenylpropyl)piperidine-4-carboxylate as its hydrochloride salt, when measured as hereinbefore mentioned, is approximately fourteen times more effective an analgesic as meperidine hydrochloride, or thus having an analgesic activity approximately fifty-six times that of the corresponding known 1-benzyl homolog. In addition to having this high analgesic activity, my compounds have a relatively low toxicity; for example, said ethyl 4-phenyl-1-(3-phenylpropyl)piperidine-4-carboxylate hydrochloride is only about two and one-half times as toxic [intravenous toxicity in mice when measured by a procedure similar to that described by Hoppe et al., J. Pharm. & Exp. Therap. 95, 502 (1949)] as meperidine hydrochloride, so that its therapeutic index compared with meperidine hydrochloride is approximately five and one-half.

The lower alkyl 4-phenyl-1-(3-phenylpropyl)piperidine-4-carboxylates in free base form, having the formula

where the lower alkyl radical has from one to six carbon atoms, are prepared by reacting a lower alkyl 4-phenylpiperidine-4-carboxylate with a 3-phenylpropylating agent such as: (a) a 3-phenylpropyl ester of a strong inorganic acid or an organic sulfonic acid; (b) 3-phenyl-2-propenal (cinnamaldehyde) under catalytic hydrogenation conditions; or (c) 3-phenylpropanal under catalytic hydrogenation conditions. Suitable 3-phenylpropylating agents of type (a) include the 3-phenylpropyl bromide, chloride, iodide, sulfate, methanesulfonate, benzenesulfonate, para-toluenesulfonate, and the like, with the bromide being preferred. This reaction is carried out by heating the lower alkyl 4-phenylpiperidine-4-carboxylate with the 3-phenylpropyl ester in the presence or absence of a suitable solvent, but preferably in the presence of a solvent such as a lower alkanol. As a specific illustration of my invention, ethyl 4-phenyl-1-(3-phenylpropyl)piperidine-4-carboxylate is obtained by heating ethyl 4-phenylpiperidine-4-carboxylate with 3-phenylpropyl bromide, preferably in refluxing n-butanol with stirring in the presence of an alkaline agent such as sodium carbonate to neutralize the hydrogen halide formed by the reaction. Since the preferred intermediate, ethyl 4-phenylpiperidine-4-carboxylate forms an insoluble carbonate when treated with carbon dioxide, a convenient way of ascertaining whether the reaction is complete or not is merely to treat the reaction mixture with carbon dioxide, the absence of a precipitate indicating completeness of the reaction. The product is isolated in free base form or in the form of its acid addition salt.

The same compound, ethyl 4-phenyl-1-(3-phenylpropyl)piperidine-4-carboxylate, is formed when ethyl 4-phenylpiperidine-4-carboxylate is reacted with 3-phenyl-2-propenal or 3-phenylpropanal and hydrogen under pressure in the presence of a hydrogenation catalyst effective to reduce carbon-to-nitrogen and carbon-to-carbon double bonds, e.g., palladium chloride on charcoal.

My new lower alkyl 4-phenyl-1-(3-phenylpropyl)piperidine-4-carboxylates are useful in the free base form or in the form of acid addition salts, and these salts are within the purview of the invention. The acids which

can be used to prepare acid addition salts are preferably those which produce, when combined with the free base, salts whose anions are relatively innocuous to the animal organism in therapeutic doses of the salts, so that the beneficial physiological properties inherent in the free base are not vitiated by side effects ascribable to the anions. In practicing my invention, I found it convenient to employ the hydrochloride salt. However, other appropriate acid addition salts are those derived from mineral acids such as hydrobromic acid, hydriodic acid, nitric acid, phosphoric acid and sulfuric acid; and organic acids such as acetic acid, citric acid, tartaric acid, lactic acid, quinic acid, methanesulfonic acid, ethanesulfonic acid, and the like, giving the hydrobromide, hydriodide, nitrate, phosphate or acid phosphate, sulfate or bisulfate, acetate, citrate or acid citrate, tartrate or bitartrate, lactate, quinate, methanesulfonate and ethanesulfonate salts, respectively.

The following examples will further illustrate the invention without, however, limiting it thereto.

EXAMPLE 1

Lower alkyl 4-phenyl-1-(3-phenylpropyl)piperidine-4-carboxylates.—The preparation of these compounds is illustrated by the following preparation of ethyl 4-phenyl-1-(3-phenylpropyl)piperidine-4-carboxylate: A mixture of 13.4 g. of ethyl 4-phenylpiperidine-4-carboxylate hydrochloride, 10.0 g. of 3-phenylpropyl bromide, 100 ml. of n-butanol and 20 g. of anhydrous sodium carbonate was refluxed with stirring for twenty-four hours. The reaction mixture was allowed to cool and was filtered. The filtrate was treated with carbon dioxide but no precipitate resulted, indicating that the reaction was complete. Then the filtrate was concentrated in vacuo and the residual oily material distilled under reduced pressure to yield 16.1 g. of ethyl 4-phenyl-1-(3-phenylpropyl)piperidine-4-carboxylate, which distilled at 148–160° C. at 0.06 mm.; $n_{D}^{27}=1.5428$.

The above-described preparation was also carried out using ethyl 4-phenylpiperidine-4-carboxylate in free base form (11.6 g.) and only one-half as much sodium carbonate (10 g.). Alternatively, this preparation can be carried out using other esters such as 3-phenylpropyl para-toluenesulfonate in place of 3-phenylpropyl bromide.

Following the above procedure but using methyl 4-phenylpiperidine-4-carboxylate, isobutyl 4-phenylpiperidine-4-carboxylate, or n-hexyl 4-phenylpiperidine-4-carboxylate in place of ethyl 4-phenylpiperidine-4-carboxylate, there is obtained methyl 4-phenyl-1-(3-phenylpropyl)piperidine-4-carboxylate, isobutyl 4-phenyl-1-(3-phenylpropyl)piperidine-4-carboxylate, or n-hexyl 4-phenyl-1-(3-phenylpropyl)piperidine-4-carboxylate, respectively.

EXAMPLE 2

Lower alkyl 4-phenyl-1-(3-phenylpropyl)piperidine-4-carboxylate acid addition salts.—The synthesis of these salts is illustrated by the following synthesis of ethyl 4-phenyl-1-(3-phenylpropyl)piperidine-4-carboxylate hydrochloride: This salt can be prepared either from the purified basic ester or directly from the above reaction mixture without first distilling the basic ester, as follows: The residual oily material (after concentration in vacuo) was treated with a slight excess of aqueous hydrochloric acid; the solution heated to boiling; decolorizing charcoal added and the mixture filtered; and the filtrate allowed to cool. The crystalline hydrochloride that separated was recrystallized from absolute ethanol, M.P. 169.5–170.6° C. (corr.).

Anal.—Calcd. for $C_{23}H_{29}NO_2 \cdot HCl$: C, 71.21; H, 7.80; Cl, 9.14. Found: C, 71.19; H, 7.91; Cl, 9.10. This hydrochloride was also recrystallized from water and from ethanol-ether.

Following the above procedure but using methyl 4-phenyl-1-(3-phenylpropyl)piperidine-4-carboxylate, isobutyl 4-phenyl-1-(3-phenylpropyl)piperidine-4-car-

boxylate or n-hexyl 4-phenyl-1-(3-phenylpropyl)piperidine-4-carboxylate in place of ethyl 4-phenyl-1-(3-phenylpropyl)piperidine-4-carboxylate, there is obtained methyl 4-phenyl-1-(3-phenylpropyl)piperidine-4-carboxylate hydrochloride, isobutyl 4-phenyl-1-(3-phenylpropyl)piperidine-4-carboxylate hydrochloride or n-hexyl 4-phenyl-1-(3-phenylpropyl)piperidine-4-carboxylate hydrochloride, respectively.

I also prepared the sulfate, phosphate, methanesulfonate, ethanesulfonate, quinate, lactate (see Example 3), tartrate and acetate salts of ethyl 4-phenyl-1-(3-phenylpropyl)piperidine-4-carboxylate.

Pharmacological evaluation of ethyl 4-phenyl-1-(3-phenylpropyl)piperidine-4-carboxylate hydrochloride in aqueous solution administered intraperitoneally or subcutaneously by the Rat Thermal Stimulus Method of Bass and Vander Brook [J. Am. Pharm. Assoc., Sci. Ed., 41, 569–570 (1952)] has shown that this compound is approximately fourteen times as active an analgesic as ethyl 4-phenyl-1-methylpiperidine-4-carboxylate hydrochloride. This compound was found to have an acute toxicity in mice of 15.8 ± 1.1 mg. per kg. when administered intravenously in aqueous solution.

EXAMPLE 3

Ethyl 4-phenyl-1-(3-phenylpropyl)piperidine-4-carboxylate lactate.—This salt was prepared by allowing a mixture of 13.3 g. of ethyl 4-phenyl-1-(3-phenylpropyl)piperidine-4-carboxylate, 4 g. of 85% lactic acid and 100 ml. of methanol to stand at room temperature. After about sixteen days, the mixture had completely crystallized. The crystalline material was collected and recrystallized from methanol to yield the product, ethyl 4-phenyl-1-(3-phenylpropyl)piperidine-4-carboxylate lactate, M.P. 80.4–83.8° C. (corr.).

Anal.—Calcd. for $C_{23}H_{29}NO_2 \cdot C_3H_6O_3$: C, 70.72; H, 7.99; O, 18.13. Found: C, 70.62; H, 8.08; O, 18.0.

Pharmacological evaluation of ethyl 4-phenyl-1-(3-phenylpropyl)piperidine-4-carboxylate lactate in aqueous solution administered subcutaneously by the method referred to in Example 2 has shown that this compound is approximately fourteen times as active an analgesic as ethyl 4-phenyl-1-methylpiperidine-4-carboxylate hydrochloride, thus having the same analgesic activity as the corresponding hydrochloride salt of Example 2.

EXAMPLE 4

Ethyl 4-phenyl-1-(3-phenylpropyl)-4-carboxylate hydrochloride.—A mixture of 11.65 g. of ethyl 4-phenylpiperidine-4-carboxylate, 7.1 g. of 3-phenyl-2-propenal (cinnamaldehyde), 70 ml. of ethanol, 9.5 ml. of water, 3.2 ml. of acetic acid, 0.46 g. of sodium acetate and palladium chloride on charcoal was treated with hydrogen at an initial pressure of 560 pounds per square inch at room temperature (17° C.). After the reduction had been completed in about forty-five minutes (final pressure, 220 pounds per square inch), the reaction mixture was filtered and to the filtrate was added 25 ml. of concentrated hydrochloric acid, followed by addition of ether until a white precipitate separated. A recrystallization of this precipitate from water gave the product, ethyl 4-phenyl-1-(3-phenylpropyl)-4-carboxylate hydrochloride, M.P. 168° C., identical with the product of Example 2.

Following the above procedure, but using 3-phenylpropanal in place of 3-phenyl-2-propenal, the same product is obtained.

My lower alkyl 4-phenyl-1-(3-phenylpropyl)piperidine-4-carboxylates can be formulated in liquid preparations, e.g., aqueous or aqueous-ethanol menstruum, or in solid form, e.g., tablet or powder. The tablet formulation can be prepared using conventional excipients; and the powder can be compounded in capsule form. These preparations can be administered orally or, in the case of the aqueous preparations, intramuscularly or intravenously.

I claim:

1. Lower alkyl 4-phenyl-1-(3-phenylpropyl)piperidine-4-carboxylates.
2. Pharmacologically acceptable acid addition salts of a lower alkyl 4-phenyl-1-(3-phenylpropyl)piperidine-4-carboxylate.
3. Ethyl 4-phenyl-1-(3-phenylpropyl)piperidine-4-carboxylate.
4. Ethyl 4-phenyl-1-(3-phenylpropyl)piperidine-4-carboxylate hydrochloride.
5. Ethyl 4-phenyl-1-(3-phenylpropyl)piperidine-4-carboxylate lactate.
6. The process of preparing a lower alkyl 4-phenyl-1-(3-phenylpropyl)piperidine-4-carboxylate which comprises reacting a lower alkyl 4-phenylpiperidine-4-carboxylate with a 3-phenylpropyl ester of a strong inorganic acid.
7. The process of preparing a lower alkyl 4-phenyl-1-(3-phenylpropyl)piperidine-4-carboxylate which com-

prises heating a lower alkyl 4-phenylpiperidine-4-carboxylate with a 3-phenylpropyl halide.

8. The process of preparing ethyl 4-phenyl-1-(3-phenylpropyl)piperidine-4-carboxylate which comprises heating ethyl 4-phenylpiperidine-4-carboxylate with 3-phenylpropyl bromide.
